UNITED STATES PATENT OFFICE.

WILLIAM RICHARD WHITE, OF BLOOMINGTON, ILLINOIS.

SWINGING GATE.

SPECIFICATION forming part of Letters Patent No. 652,870, dated July 3, 1900.

Application filed September 25, 1899. Serial No. 731,629. (No model.)

To all whom it may concern:

Be it known that I, WILLIAM RICHARD WHITE, a citizen of the United States, residing at Bloomington, in the county of McLean 5 and State of Illinois, have invented certain new and useful Improvements in Swinging Gates, of which the following is a specification.

This invention relates to certain new and 10 useful improvements in swinging gates; and it consists, substantially, in such features of construction, arrangement, and combination of parts as will hereinafter be more particularly described, reference being had to the 15 accompanying drawings, in which—

Figure 1 is a perspective view of a swinging gate and its operating mechanism made in accordance with my invention. Fig. 2 is a plan view of the gate. Fig. 3 is a plan view 20 of a portion of the latch-bar. Fig. 4 is a vertical section through the gate.

The gate A, as shown, consists of upper and lower longitudinal rails 1 and 2, formed, preferably, of channel-iron, with the channels 25 posing each other, the uprights 3, diagonal braces 4, and longitudinal rods or bars 5, extending through openings in the uprights and braces. The ends of the uprights and braces are bent to lie one upon the other in the channels of the top and bottom rails and are secured to the rails by rivets 6 or other suitable means. This makes a very neat finish, as the bent ends of the uprights and braces are 30 hidden within the channels and a smooth unbroken outer surface is presented.

The rods or bars 5, with the exception of the latch-bar, are secured against longitudinal movement by any suitable means—as, for instance, by burring or otherwise forming a 40 head 7 on one end to engage the outer face of one end upright and threading the other end for the reception of a nut 8 to engage the outer face of the other end upright. In this way the rods can readily be removed, if necessary. However, both ends may be burred or 45 headed, if preferred, or other means be employed to secure the rods in place.

One of the rods 5, preferably the upper one, will have a horizontally-disposed U-shaped loop 9 formed in it near the hinge end 50 of the gate, this loop forming a fulcrum for the arm which operates the latch-bar, as will be referred to hereinafter. The rod or bar immediately below this is the latch-bar and

is mounted to have longitudinal movement 55 in the uprights and braces. This rod is also provided with a horizontally-disposed U-shaped loop 10, extending oppositely to the loop 9 and in substantially the same vertical plane. Near the other end of the gate the 60 latch-bar is bent to form an upwardly-extending loop 11 to serve as a handhold. To facilitate the insertion of the latch-bar through the uprights and braces, it will preferably be made in two sections united by a coupling- 65 sleeve 12, into which the adjacent ends of the two sections will be screwed.

The latch consists of a vertically-disposed spring strip or rod 13, which is bent at its ends and the bent portions secured to the upper 70 and lower rails 1 and 2. This spring-latch is so arranged that normally it will operatively engage the catch 14, and to be disengaged must be put under tension. The latch-bar is extended beyond the end upright and connected to the latch in any suitable manner, preferably by nuts 15 on opposite sides of the latch. The latch-bar must necessarily fit loosely in its bearings in the uprights and braces in order that it may slide freely there- 75 in, and the loop 11, which forms the handhold must, in order that it may be most conveniently grasped from either side of the gate, extend vertically either above or below the latch-bar. It is obvious that in opening the 80 gate by hand the pressure exerted on the handhold will naturally tend to pull the loop 11 out of its vertical position, and thus turn the latch-bar in its bearings. This tendency to turn will in a measure be resisted by the nuts 85 15 if both are screwed tightly against the latch; but either of said nuts is liable to turn away from the latch, and thereby make a loose connection between the bar and latch. Any turning of the bar will naturally disturb the 90 connection between the coupling 12 and the two sections of the latch-bar, and in the course of time this will result in one of three things—either the latch-bar will be unduly shortened, or it will be unduly lengthened, or the coup- 95 ling will become disconnected from one of the sections of the latch-bar, with the effect in either case of interfering with the proper operation of the gate. Some means must therefore be provided to positively prevent the 100 latch-bar from turning in its bearings without interfering with its longitudinal movement, and this I accomplish by bending the

end of the bar beyond the end of the gate to form a crank 16 between the end upright and the latch. This also results in bringing the connection between the latch and latch-bar 5 lower down, so that the catch may be arranged to engage the latch about midway the length of the latter.

It is obvious that the crank 16 may be formed in the latch-bar between any two of its supports; but the construction shown is preferable, as it does not mar the symmetrical appearance of the gate between the end uprights. It is also obvious that the catch could be turned or reversed so as to have the notch 15 adjacent to the end of the gate and cause the latch to move toward the end of the gate to engage with it instead of moving away from the gate, or the catch could be made in the form of a spear-head, with a notch on either 20 side, so that the latch could move either toward or from the gate, as desired, the movement of the latch-bar being regulated to correspond with the direction in which it is desired to have the latch move.

25 The gate may be hinged to the post 17 in any suitable manner and is adapted to swing against the posts 18 and 19, each of which is provided with a catch 14.

The operating hand-levers for the gate are 30 indicated by 20, one being pivoted intermediate its ends to a post 21 and the other to a block 22, projecting diagonally from a post 17. A tie-bar 24 is fastened to the upper ends of the posts 21 and 17 and the outer end of 35 the block 22, and this, together with braces 25 and guiding-loop 26, insures a firm support for the levers 20 and prevents any undue lateral motion. The opposing ends of 40 the levers are loosely connected by means of a pin 27, pivoted in a slot 28 in one lever and extending loosely into a hole 29, formed in the end of the other lever and extending lengthwise thereof. By pulling on either lever at its outer end the opposing ends, which 45 normally sag downward, will both be lifted. The arm which transmits movement from the levers 20 to the latch-bar is indicated by B, and, as shown, it consists of a metal bar or 50 rod *a*, having an eye *b* at its upper end and bent into the form of a crank-handle *c* at its lower end. It is also provided with a lateral extension *d*, and the latter is bent to form a 55 journal *e*, which lies substantially parallel to the middle portion of the arm and which has a bearing in an opening formed in the top rail of the gate and forms a pivot about which the arm may turn. The crank-handle portion of the arm engages the U-shaped loops 9 and 10, and 60 when the arm B turns on its pivot the loop 9 acts as a fulcrum upon which the crank rocks, and the latch-bar is thus moved longitudinally to operate the latch. A link 27^a is pivotally connected at one end to the eye *b* and at its other end to an eye 28^a, secured to one 65 of the levers 20.

The U-shaped loops on the rods or bars 5 and the shape of the arm B and manner of

mounting on the gate and engaging it with the U-shaped loops insure a positive movement of the latch-bar, with little friction and 70 little lost motion between the operating parts.

It is obvious that the crank-shaped portion of the latch-bar will effectually prevent the bar from turning in its bearings, and consequently the connections between the coupling 75 12 and the two sections of the latch-bar will not be disturbed and the loop 11 will maintain its vertical position to be easily grasped by a person on either side of the gate.

Without limiting myself to the precise details of construction and arrangement shown and described, I claim as my invention—

1. In a gate, the combination with the uprights and the latch, of a cross-sectionally-round latch-bar connected to the latch and supported in said uprights to slide longitudinally therein, said bar being formed of two sections, one of which is provided with a vertically-disposed loop forming a handhold and a crank-shaped portion between two of its supports, and the other section having a horizontally-disposed loop with which a latch-actuating arm engages, and a coupling into which the opposing ends of the sections are screwed, substantially as set forth. 95

2. In a gate, the combination with the uprights and the latch, of a cross-sectionally-round latch-bar connected to the latch and supported in said uprights to slide longitudinally therein, said bar having a vertically-extending loop near one end to form a handhold, and a crank-shaped portion between two of its supports to prevent it from turning in its bearings, substantially as set forth. 100

3. In a gate, the combination with a fixed, 105 longitudinally-extending bar having a horizontally-disposed loop formed therein, of a sliding latch-bar having a horizontally-disposed loop extending oppositely to the loop in the fixed bar, a latch connected to the latch-bar, an arm pivoted in the gate and having a crank-shaped portion engaging the loops, and means to actuate the arm, substantially 110 as set forth.

4. In a gate, the combination of the operating-levers 20, an arm having an eye at its upper end, a crank-shaped lower end, and a lateral extension supported in the top rail of the gate and forming a pivot about which the arm may turn, a link connected to said eye 115 and one of the levers, a fixed bar in the gate having a horizontally-disposed loop, a sliding latch-bar also having a horizontally-disposed loop, said loops extending in opposite directions and being engaged by the crank-shaped 120 portion of the arm, substantially as set forth. 125

In testimony whereof I have signed my name to this specification in the presence of two subscribing witnesses.

WILLIAM RICHARD WHITE.
